VENDING MACHINE

Walter L. Koch, Caldwell, N.J., assignor to Automatic Canteen Company of America, Chicago, Ill., a corporation of Delaware

Filed Apr. 21, 1964, Ser. No. 79,623

Term of patent 14 years

(Cl. D52—3)

The rear of the vending machine is substantially flat and plain.

I claim:

The ornamental design for a vending machine, as shown and described.
